UNITED STATES PATENT OFFICE.

JOHN SPAULDING, OF MOUNT HOLLY, VERMONT.

IMPROVEMENT IN WATER-WHEELS.

Specification forming part of Letters Patent No. 44,230, dated September 13, 1864.

To all whom it may concern:

Be it known that I, JOHN SPAULDING, of Mount Holly, in the county of Rutland and State of Vermont, have invented an Improved Screw Water Wheel or Motor; and I do hereby declare the same to be fully described in the following specification, and represented in the accompanying drawings, of which—

Figure 1 is a vertical section of my improved motor as arranged within its case. Fig. 2 is a side elevation, and Fig. 3 a lower end view, of the wheel or motor.

My said wheel or motor, in the main, is constructed like what is termed a "twist-auger," or, in other words, it has a long plate twisted and extended from a shaft, the axis of the shaft and the twist being a straight line or in prolongation of one another. This twisting of the plate gives to the motor two helical channels to flow through, one of which inter-twists or interwinds with the other. These channels as they descend are to diminish in width in cross-section, each being smaller at bottom than at top.

In the drawings, A denotes the twist-auger wheel or motor, and B its tubular casing, by which it is surrounded and within which it revolves, such casing leading vertically out of a flume or conduit, C. The central part of the lower extremity of the motor has a pivot, a, to rest in a step, b, the shaft, f being supported in a bearing, g. The two diminishing spiral channels of the motor are shown at c d.

I have found that when the channels are diminished in cross-section as they descend the water will operate with greater useful effect on the motor to rotate it than when each of its channels is made of equal width throughout.

The ratio of diminution to produce the most useful effect I have not been able to discover, but I have found the contraction of the channel at its lower end to be at or about at one-third of what it is at its upper end or middle to operate to good advantage. The water, by running through two separate helical channels, intertwisted, as set forth, operates with much better results than when suffered to flow in one helical channel only, as it insures a greater steadiness and regularity of motion of the motor, and by acting on more extended surfaces can operate with less loss of power.

I do not claim the employment of a single screw in a tubular case as a motor or wheel to be operated by the gravitating force of water when allowed to flow through the said case.

I claim—

The improved twisted-plate auger motor or water-wheel, as made in manner and with diminishing channels, and to operate substantially as described.

JOHN SPAULDING.
